UNITED STATES PATENT OFFICE.

DANIEL B. REARDON, OF COUNCIL BLUFFS, IOWA.

ROAD MAINTAINER.

Application filed September 27, 1920. Serial No. 413,025.

To all whom it may concern:

Be it known that I, DANIEL B. REARDON, a citizen of the United States, residing at Council Bluffs, in the county of Pottawattamie and State of Iowa, have invented certain new and useful Improvements in Road Maintainers, of which the following is a specification.

The present invention relates to road maintainers, or to a device adapted for use in scraping and maintaining in a relatively smooth condition the upper surface or carpet of a road.

An object of the present invention is to provide a device of this character with means whereby the scraper or surface treating implement may be adjusted as to its transverse angle with respect to the length of the device, and wherein such adjustment may be effected by the forward movement of the device combined with the weight of the implement so that all mechanism and power is eliminated which is ordinarily required in the adjustment of the transverse angle of the implement.

Another object of the invention is to provide a road maintainer or surface scraper of this type with means permitting the utilization of the weight of the operator for holding the implement in contact with the road surface and in the provision of means under the control of the operator for raising and lowering the opposite ends of the implement for effecting desired variations in the horizontal level of the road surface.

A further object of the invention is to provide an improved construction wherein the implement or scraper is supported against undue thrust or strain at opposite ends and at all positions of adjustment so that there is always a straight line pull of reinforcement for the opposite ends of the scraper. This feature of the invention also embraces the provision of braces or supports for the opposite ends of the implement and which are mounted and constructed to yield or vary to a predetermined extent for taking up inequalities in the roadway, obstructions and the like which tend to temporarily lift the opposite ends of the implement.

With the foregoing and other objects in view, the invention will be more fully described hereinafter, and will be more par-

ticularly pointed out in the claims appended hereto. 55

In the drawings, wherein like symbols refer to like or corresponding parts throughout the several views,

Fig. 1 is a top plan view of a road maintainer constructed according to the present invention;

Fig. 2 is a top plan view of a brace rod forming a part of the structure;

Fig. 3 is a fragmentary enlarged side elevation of a portion of the frame and the adjustable connection between the frame and the brace rod shown in Fig. 2; 65

Fig. 4 is a side elevation of the device;

Fig. 5 is a transverse section taken substantially in the plane indicated by the line 5—5 in Fig. 4 and showing the independently operable elevating devices connected to the opposite ends of the implement or scraper; 70

Fig. 6 is a transverse section taken substantially in the plane indicated by the line 6—6 in Fig. 3; and 75

Fig. 7 is a side elevation of the brace rod of Fig. 2.

Referring to these drawings, wherein like parts are designated by similar characters of reference throughout the several views, 80 10 designates the frame of the machine and which is preferably constructed of a length of channel iron bent substantially U-shaped 85 with elongated side portions and with a rounded forward end 11 of relatively small radius. The rear end of the frame 10 is closed by a transverse brace bar 12 bolted or otherwise suitably secured to the extremities 90 of the frame 10, and which serves as a support for a pair of depending brackets 13 which carry the rear axle 14. Suitable wheels 15 are mounted on the axle for supporting the rear end of the frame. 95

The rounded forward end 11 of the frame is provided with a substantially semi-circular bottom plate 16 and a correspondingly shaped top plate or platform 17. These two plates are secured against the top and bottom edges of the frame 10 and provide a suitable support for a vertical spindle 18 which rises through the central portions of the plates 16 and 17 and which carries a bolster 19 upon its lower end and to which is secured the front axle 20. 100 105

The front axle 20 carries a pair of road engaging steering wheels 21 adapted for swinging movement at the sides of and beneath the frame 10 for guiding the frame 5 and admitting of the turning of the same on a short radius. A clevis 22, draw bar, or the like may be secured to the front of the bolster 19 and may be attached to a traction engine or to any suitable draft rigging used 10 for the drawing of the machine over the surface of the road.

The frame 10 carries an intermediate transverse brace 23 having substantial width and carrying upon its under side a depending plate or support 24 which at its upper end is bolted or otherwise suitably and rigidly secured to the brace 23. Spaced apart 15 strap bearings 25 project from one side of the support 24 and are arranged in vertical alignment for the reception of a tubular post 26. The upper end of the post is reduced and threaded to provide a stem 27 which projects upwardly through an opening in the brace bar 23. The stem 27 also projects 20 upwardly through a preferably wooden cross bar 28 which extends over and between the sides of the frame 10 and upon which the tubular post 26 is supported by means of a pin 29 which is secured transversely through 25 the upper end of the stem 27. The cross piece 28 frictionally engages against the tops of the side bars 10 and yieldingly holds the scraper in adjusted position.

On each end of the cross piece 28 is arranged an inwardly and rearwardly projecting handle 30 of desired length and fulcrumed near its forward end on a pin 31 carried by the brace 28. The forward end of 35 each handle 30 is relatively short and has attached thereto the upper end of a cable or other flexible connector 32 which is engaged with an eye 33 at its lower end and which eye is mounted upon the adjacent end of a transversely extending scraper.

40 The scraper is formed of two or more substantially U-shaped brackets 34 spaced apart near the opposite ends of the scraper and which support a platform or board 35 upon which the operator may stand and which is secured by bolts 36 in position on the brackets 34. The brackets 34 open forwardly and their free ends are held apart in suitable spaced relation by sleeves 37 which are clamped or otherwise suitably secured between the free ends of the brackets. The 45 lower portions of the brackets 34 are extended beyond the upper portions thereof and are preferably bent down at a desired angle for engagement with and securing to the rear edge portion of a concaved scraper blade 38 supported by the brackets 34 upon the frame of the machine.

46 The scraper blade 38 is of convex form throughout its length and has a lower cutting edge adapted to drag or scrape upon the up-

per surface of the roadway, whereby to even such surface, and the position of weight upon the platform 35 is adapted to regulate or control the pressure and depth at and to which the scraper operates upon the road. 70

While the flexible supports 32 support the scraper blade 38 at opposite ends and may be adjusted by the hand levers 30 to raise and lower the ends of the scraper blade, means is provided for supporting the scraper blade 75 at the desired transverse angle with respect to the length of the machine. The means comprises a pair of brace rods 39 pivotally connected at their lower ends to the upstanding sleeves 37 at opposite ends of the scraper 80 blade 38. The brace rods 39 project upwardly and forwardly toward the sides of the frame 10 and have on their upper ends T-heads 40 lying substantially in planes at right angles to the axes of the brace rods 39 85 and which are adapted to enter through slots 41 formed in the outer sides of a pair of slides 42 which are mounted for longitudinal sliding movement upon the opposite sides of the frame 10. 90

The slots 41 are substantially horizontal and the brace rods 39 are adapted to be interlocked upon the slides 42 by introduction of the heads 40 and through the slots 41 when the brace rods 39 are in substantially 95 vertical position. By swinging the brace rods 39 into their normal position for operation such as shown in Fig. 4, the heads 40 are turned in the slides 42 into a position out of registry with the slots 41 so that the 100 heads are thus interlocked in the slides and are permitted a sliding movement in the slide sufficient to compensate for normal inequalities in the road.

As shown to advantage in Fig. 6, the channel bar to which the frame 10 is formed has its flanges projecting outwardly to provide a channel at the outer side of the frame. The slide 42 is in the form of a metal plate having its upper and lower longitudinal 110 edges bent inwardly to overlap the top and bottom edges of the frame bar 10, and angle plates 43 are bolted or otherwise suitably secured to the flanges of the slide 42 and are adapted to lap over against the inner side of 115 the frame 10 for slidably holding the slide 42 to the frame. The slide 42 is thus of hollow construction to accommodate the head 40 of the adjacent brace rod 39, and the slides 42 are connected together by a chain 120 44 or the like which is carried in the channel of the frame 10 about the forward rounded end thereof.

The rear ends of the chain are each provided with an attaching bar 45 which projects into the forward end of the adjacent slide 42 and is secured to the slide by a bolt 46 or the like. Thus, when one slide is moved rearwardly the opposite slide is drawn forwardly. In order to adjust the 130

5 slides 42 lengthwise of the frame the rear end portion of the slides are connected to cables or other flexible elements 47 which are carried rearwardly in the channel of the frame into a position substantially in line with the intermediate cross brace 23.

At this point the cables 47 are carried inwardly toward each other and are preferably interconnected, or the cable 47 may be 10 made in one continuous length secured at opposite ends to the slides 42 and are adapted to maintain the chain 44 taut and to hold the slides 42 from shifting forwardly upon any pressure of the brace rods 39 to shift the 15 slides forwardly or from any other cause.

The slides 42 are held from shifting by a latch adapted to interlock with the chain 44. The latch comprises a bar 48 which is 20 slidably mounted within the forward end of the frame 10 and preferably between the plates 16 and 17, and with its nose projecting through an opening in the web of the frame to admit the projection of the latch 48 into 25 openings 49 of the chain to lock the chain from longitudinal shifting.

The latch bar 48 may be provided with branch arms 50 on its rear end supporting springs 51 normally urging the latch bar 48 to move forwardly, and the arms 50 may 30 have connected thereto a pull rope 52 which extends rearwardly of the frame and in position for easy access of the operator for releasing the chain.

In the operation of the device the cables 35 32 may be adjusted to relatively position the scraper blade 38 for contact with the surface of the road. When this relative position is obtained the handles 30 may be operated as desired to tilt the scraper 38 to 40 conform with the inclination or curvature of the road surface and the scraper may thus be vertically adjusted.

When it is desired to change the inclination of the scraper blade 38 transversely of 45 the machine it is only necessary to draw the rope 52 and release the latch 48 from the chain 44. When thus released one of the handles 30 may be depressed to elevate one end of the scraper blade and allow the other 50 end to drag in the road. The friction between the road and the lower end of the scraper blade is such that said end of the scraper will be moved rearwardly, and as the chain 44 is released the slides 42 may 55 thus be shifted.

When the desired inclination is had the pull rope 52 is released and the springs 51 snap the latch 48 into interlocking engagement with the chain and thus hold the parts 60 in the new position.

I do not wish to be restricted to the size, form, and proportions of the various parts, and obviously changes could be made in the construction herein described without de- 65 parting from the spirit of the invention, it

being only necessary that such changes fall within the scope of the appended claims.

What is claimed is:

1. In a road maintainer, a wheeled frame, a scraper arranged beneath the frame, slides 70 mounted on opposite sides of the frame, a flexible device connecting the slides one to the other and engaging about the forward end of the frame to advance one slide upon the backward shifting of the other, 75 braces pivotally connecting the slides to the opposite ends of the scraper for maintaining the latter in adjusted position when the slides are shifted, and means for elevating one end of the scraper whereby to permit the 80 other end of the scraper to drag in the roadway and shift said slides for changing the angular relation of the scraper to the wheeled frame, and means for locking the slides in adjusted position. 85

2. In a road maintainer, a wheeled frame, a scraper arranged beneath the frame, a pair of handles mounted on the frame, flexible connectors extending from the handles to the opposite ends of the scraper whereby 90 upon tension of the handles the ends of the scraper may be independently raised and lowered, bracing means arranged at opposite sides of the frame and connected to the opposite ends of the scraper, said bracing 95 means being shiftable lengthwise of the frame for changing the angular relation of the scraper to the frame, said scraper being adapted to be elevated at one end whereby the other end of the scraper is adapted to 100 drag in the roadway and shift the scraper into the desired angular relation to the wheeled frame, and means for locking the adjustable braces to the frame.

3. In a road maintainer, a wheeled frame, 105 a transverse scraper arranged beneath the frame, adjustable depending supports carried by the frame and engaging the opposite ends of the scraper, and shiftable braces carried upon the opposite sides of the frame 110 and having connection with the opposite ends of the scraper whereby upon the dragging of one end of the scraper said braces are adapted to be shifted for changing the angular relation of the scraper with respect 115 to the wheeled frame.

4. In a road maintainer, a wheeled frame, a transverse scraper beneath the frame, depending supports carried by the frame and connected to the opposite ends of the scraper, 120 bracing means adjustably carried upon the opposite sides of the frame and having connection with the opposite ends of the scraper, said scraper being adapted to drag at one end in the roadway for shifting the 125 scraper into the desired angle relatively to the frame, and means for locking said bracing means in adjusted position on the frame.

5. In a road maintainer, a wheeled frame, 130 a pair of slides mounted upon the opposite

- 5 sides of the frame, a brace hinged to each slide and projecting downwardly and rearwardly therefrom, a scraper, means connecting the opposite ends of the scraper to the lower ends of said braces, means connecting said slides together to move one forwardly as the other is moved rearwardly for changing the angular relation of the scraper beneath the frame, and independent 10 means connected to the opposite ends of the scraper for elevating said ends whereby one end of said scraper is adapted to be elevated and the other end adapted to drag in the roadway for changing the angular relation 15 of the scraper beneath the frame.
6. In a road maintainer, a wheeled frame, a post mounted for rotation intermediate the ends of the frame, a transverse beam pivoted upon the post and adapted to rest at 20 its opposite end portions upon the sides of the frame and adapted to be slid over the frame into various transverse angular relations thereto, cables depending from the opposite ends of said beam, handles connected 25 to the cables for raising and lowering the same, a scraper connected at opposite ends to said cables and adapted to hang thereon and to assume the angular relation of said beam, slides movably mounted upon the opposite sides of the frame, means for locking 30 the slides in adjusted position, and connections between the slides and the opposite ends of the scraper whereby when said slides are released said scraper is adapted to drag 35 at one end in the roadway for changing the angular relation of the scraper and its supporting beam relatively to the frame, said locking means being adapted to secure said slides in adjusted position.
- 40 7. In a road maintainer, a wheeled frame including a channel bar rounded at the forward end of the frame and providing an outwardly facing channel, a pair of slides mounted on the channel bar at opposite 45 sides of the frame, a chain connecting said slides together and extending in said channel around the forward end of the frame, a pair of braces pivoted upon the slides, a scraper attached at opposite ends to the free ends of the braces and adapted to be drawn forwardly thereby, and adjustable suspension means carried by the frame and connected to the opposite ends of the scraper for independently and 55 vertically adjusting the opposite ends thereof.
8. In a road maintainer, a wheeled frame having a rounded forward end and an exteriorly facing channel in said end, a pair 60 of slides mounted on the sides of the frame, a chain connecting said slides together and extending around the forward end of said frame in the channel, locking means normally engaging said chain to maintain the 65 same against a sliding movement, a scraper

suspended beneath the intermediate portion of the frame and adapted to be raised and lowered at opposite ends, and braces connecting the opposite ends of the scraper to the respective slides for holding the 70 scraper in the desired transverse angular position relatively to the frame, and a latch engaging said chain to hold the same against sliding movement for retaining the slides in the desired position of adjustment. 75

9. In a road maintainer, a wheeled frame having a rounded forward end and a channel in the frame, a slide mounted on each side of the frame, a chain connecting the slides and extending in said channel around 80 the forward end of the frame, a latch carried by the frame adapted to interlock with said chain for maintaining it from sliding movement, means for retracting the latch, a scraper pivotally mounted upon the frame 85 and depending therefrom, braces between the opposite ends of the scraper and said slides for supporting the scraper, and means for raising and lowering the opposite ends of the scraper whereby one end of the 90 scraper may be lowered to drag on the roadway and said latch may be released for changing the angular position of the scraper beneath the frame, said latch being adapted to interlock with the chain when the scraper 95 is adjusted for maintaining the scraper in such position.

10. In a road maintainer, a wheeled frame, a scraper suspended beneath the frame, bracing means mounted on opposite sides of the frame for longitudinal adjustment, means connecting said bracing means for effecting the same relative forward and rearward adjustment thereof, locking means for the bracing means to maintain the same 105 in adjusted position, and means for raising and lowering the opposite ends of the scraper, whereby said scraper may be lowered at one end into engagement with the roadway and said bracing means may be released to shift said scraper by frictional contact with the roadway into the desired angular adjustment beneath the frame, said locking means being adapted to hold the bracing means in adjusted position. 110 115

11. In a road maintainer, a wheeled frame, a scraper suspended beneath the middle portion of the frame, a pair of slides mounted for longitudinal movement on the opposite sides of the frame, a connection between the 120 slides adapted to proportionately move the opposite slides forwardly and rearwardly in alternate relation upon the frame, braces carried by the slides, connections between the braces and the opposite ends of said 125 scraper whereby to support the opposite ends of the scraper upon the forward movements of the frame, and means for locking the slides in adjusted position.

12. In a road maintainer, a frame, a slide 130

- mounted upon the frame and having an elongated slot therein, a scraper carried by the frame, a brace adapted for connection at one end with the scraper to support it against longitudinal displacement, said brace having a T-head upon its other end adapted for insertion through said slot when said brace is swung into a position to dispose said T-head in registry with the slot, said T-head being adapted to interlock the brace within the slide and permit sliding longitudinal movement of the brace relatively to the slide for taking up inequalities in the surface of the roadway.
13. In a road maintainer, a wheeled frame, a scraper suspended beneath the intermediate portion of the frame, a pair of slides mounted upon the opposite sides of the frame near the forward end thereof, a chain connected at opposite ends of the slides and extending around the forward end of the frame, a spring latch normally interlocking with the chain to hold the same against sliding movement, braces carried by the slides connected to said scraper, and means for releasing said latch whereby said scraper may be shifted into various angular
- positions transversely beneath the frame, said latch being adapted to automatically interlock with said chain for maintaining the slides and the scraper in adjusted position.
14. In a road maintainer, a wheeled frame, a scraper suspended beneath the intermediate portion of said frame, a slide mounted upon each side of the frame near the forward end thereof, a chain connecting said slides together and extending about the forward end of the frame, a flexible connector extending transversely through the intermediate portion of the frame and connected at opposite ends of said slides whereby to maintain said chain under tension at all times, and a pair of braces carried by said slides and connected to the opposite ends of said scraper for supporting the same in various angular adjustments transversely beneath the frame.
- In testimony whereof, I have affixed my signature in presence of two witnesses.

DANIEL B. REARDON.
